US0D1098998S

(12) **United States Design Patent** (10) Patent No.: **US D1,098,998 S**
(45) Date of Patent: ** Oct. 21, 2025

(54) **WHEEL**

(71) Applicant: **Atturo Tire Corp.**, Waukegan, IL (US)

(72) Inventor: **Michael Mathis**, Wadsworth, IL (US)

(73) Assignee: **Atturo Tire Corp.**, Waukegan, IL (US)

(**) Term: **15 Years**

(21) Appl. No.: **29/932,865**

(22) Filed: **Mar. 15, 2024**

(51) LOC (15) Cl. **12-16**

(52) U.S. Cl.

USPC **D12/213**

(58) Field of Classification Search

USPC D12/204, 208, 213

See application file for complete search history.

CLAIM

The ornamental design for a wheel as shown and described.

DESCRIPTION

FIG. 1 is a perspective view of my design;

FIG. 2 is a front view thereof;

FIG. 3 is a rear view thereof;

FIG. 4 is a side view thereof;

FIG. 5 is another side view thereof;

FIG. 6 is a top view thereof; and,

FIG. 7 is a bottom view thereof.

The portions shown in broken lines form no part of the claimed design.

1 Claim, 6 Drawing Sheets
